LUG STRAP FOR LOOMS

Filed May 12, 1931

FIG. 2.

FIG. 1.

FIG. 3.

FIG. 4.

Inventor:
Homer F. Livermore,
by

Parker S. Gooding, Atty.

UNITED STATES PATENT OFFICE

HOMER F. LIVERMORE, OF BROOKLINE, MASSACHUSETTS, ASSIGNOR TO GUARANTEED PARTS, INC., OF ALLSTON, MASSACHUSETTS, A CORPORATION OF MASSACHUSETTS

LUG STRAP FOR LOOMS

Application filed May 12, 1931. Serial No. 536,753.

This invention relates to an improvement in lug straps for looms.

The object of the invention is to provide a lug strap of novel construction embodying therein a pair of side bars between which is located an adjustable striker member, the latter being preferably cylindrical in form and being so secured to the side bars that it may be rotated therebetween in order that different portions of its periphery may contact with a picker stick or be engaged by a pick arm as said periphery becomes worn, the result being that the life of the lug strap is greatly prolonged.

Another object of the invention is to provide an improved hold-up member by means of which the lug strap is connected to an intermediate portion of the picker stick.

The invention consists in an improved lug strap for looms as set forth in the following specification and particularly as pointed out in the claims thereof.

Referring to the drawing:

Fig. 1 is a side elevation of an intermediate portion of a picker stick, an end portion of a sweep stick, and a lug strap and hold-up member therefor embodying my invention.

Fig. 2 is a sectional plan view taken on the line 2—2, Fig. 1.

Fig. 3 is a transverse sectional elevation taken on the line 3—3 of Fig. 1.

Fig. 4 is a detail transverse section taken on the line 4—4 of Fig. 1.

Like numerals refer to like parts throughout the several views of the drawing.

In the drawing, 5 represents an intermediate portion of a picker stick of well-known form, 6 an end portion of a sweep stick also of well-known form, and 7 is a lug strap which is secured by means of a bolt 8 to the sweep stick, and is connected, in a manner hereinafter to be described, to the picker stick.

The lug strap 7 embodies therein a pair of side bars 9 which may be either rigid or flexible. When rigid they may be made of a light strong metal. When flexible they may be made of leather, or layers of fabric secured together by a suitable adhesive. The

side bars 9 are located upon opposite sides of the picker stick 5 and their outer end portions are secured together by means of a bolt 10 which extends through a cylindrical sleeve 11 which also functions as a spacing member 55 to space the outer end portions of the bars 9 a predetermined distance apart.

Rotatably mounted upon the sleeve 11 between the side bars 9 is a striker 12 also cylindrical in form, and this striker is clamped 60 between the bars 9 by means of the bolt 10. The striker may be constructed of leather, rubber, fabric, or any other tough material capable of withstanding excessive wear, and the periphery thereof is adapted to contact 65 with an edge of the picker stick. As the periphery of the striker 12 becomes worn from continual contact with the edge of the picker stick, the striker may be rotated upon the sleeve 11 between the bars 9 and an un- 70 worn portion of its periphery moves into position to engage the picker stick, the bolt 10 being first loosened to permit the striker 12 to be rotated, and then tightened in order 75 that said striker will be clamped between the bars 9.

The lug strap 7 is supported at a proper position upon the picker stick 5 by means of a plate 13 which constitutes a hold-up member, said plate being provided with oppositely disposed notches 14 in which the bars 9 are located. The plate 13 is clamped to an edge of the picker stick 5 by means of a yoke 15 which encircles the picker stick and which is secured to the latter by means of a set screw 80 16. In adjusting the plate 13 upon the picker stick 5 all that is necessary is to loosen the set screw 16 a sufficient amount to permit the plate to slide upon the picker stick beneath the yoke 15, after which said yoke is tightened 85 against the plate by again tightening the screw 16.

In the operation of the loom, when the striker 12 has become worn to such an extent that the proper operation of the picker stick is 90 affected, the bolt 10 is loosened and the striker 12 is rotated upon the sleeve 11 between the bars 9 a sufficient amount so that an unworn portion of the periphery of the striker will engage the picker stick and the striker is then 95 100

clamped in this position by tightening the bolt 10.

While I have illustrated the lug strap of this invention as being attached at one end only of a sweep stick for the purpose of engaging the picker stick and causing the latter to be actuated, in certain types of looms a separate lug strap may be secured at each end of the sweep stick, one of said lug straps being adapted to engage the picker stick and the other of said lug straps being adapted to be engaged by the pick arm, and it will be understood that in certain of the claims the actuated member mentioned has reference to the picker stick and the actuating member mentioned refers to the pick arm.

I claim:

1. A lug strap of the character described having, in combination, a pair of side bars, 20 a rigid spacer for said side bars, whereby the latter are positioned a predetermined distance apart, a flexible striker member mounted to rotate upon said spacer, and means to clamp the spacer and striker member between 25 the side bars.

2. A lug strap of the character described having, in combination, a pair of side bars, a non-compressible sleeve interposed between said bars and spacing the latter a predetermined distance apart, a flexible striker member 30 rotatably mounted upon said sleeve, and a bolt extending through the side bars and sleeve and clamping the sleeve and striker between the side bars.

3. In combination, a sweep stick, a pair of side bars attached at one end thereof to said sweep stick, a sleeve interposed between said bars at the other end thereof and spacing the bars a predetermined distance apart, a picker stick located between said side bars, a hold-up plate fast to said picker stick and engaging said side bars, a striker rotatably mounted upon said sleeve and means to clamp said sleeve and striker between the bars whereby 45 different portions of the periphery of the striker may be presented to the picker stick.

In testimony whereof I have hereunto set my hand.

HOMER F. LIVERMORE.
